ORNAMENT

William Huppert, New York, N. Y., assignor to
Delamere Company, Inc., a corporation of Dela-
ware

Application June 11, 1940, Serial No. 339,853

8 Claims. (Cl. 41—13)

This invention relates to an ornament, and more particularly to an ornament for personal wear.

The principal object is to provide an ornament of novel and simple construction which is intended primarily to be worn in women's or children's hair in the manner of an ornamental hairpin or barrette, and which may be used for other ornamental purposes, as for instance to be worn on the lapel of a man's or woman's coat as a simulated boutonniere.

The device comprises an ornamental body, which may be in the form of an imitation flower, or in any other form, mounted on the bight end of a conventional spring clasp. The present invention is concerned principally with the assembly of the ornamental body and the spring clasp.

An embodiment of the invention is illustrated in the accompanying drawing, in which:

Figure 1 is a perspective view of the completely assembled ornament;

Fig. 2 is a perspective view of the parts thereof prior to assembly;

Fig. 3 is a side elevation of the ornament, partly in section; and

Fig. 4 is an enlarged cross-section taken on the line 4—4 of Fig. 3, viewed in the direction of the arrows.

The device includes a conventional spring clasp of the hairpin or so-called bobby pin type, consisting of a single piece of spring metal bent to form two legs 10 and 11 having a connecting bight 12. The leg 11 may be somewhat longer than the other leg and may have its extremity 13 slightly curved. The leg 10 may be covered on its outer face, or entirely, with a covering 14 of molded plastic substance or other suitable material of any desired color which covering may extend over, or part way over, the bight 12. The covering 14, however, is not essential and may be omitted.

15 represents a hollow ornamental body which is preferably made of molded plastic substance, but which may be made of metal or other suitable material, and shaped in imitation of a flower or of any other desired ornamental object. The body 15 has an interior cavity 16, an opening 17 through one wall, and a second opening 18 through the bottom or through a point suitably spaced from the opening 17. The ornament may be made of colored material or may be otherwise colored. In the present instance, the ornament is shown, for the purpose of illustration but not 55 of limitation, in the form of a calla lily.

In assembling the parts, the spring clasp is inserted in the cavity 16 of the body 15, with the leg 11 passing through the opening 17 and the leg 10 passing through the opening 18. The ornament is then slid lengthwise on the clasp, or 5 the clasp is slid lengthwise relative to the ornament, until the bight 12 of the clasp is caught in the opening 17, as seen in Fig. 3. In this position the ornament is supported on the bight 12 and is held against endwise displacement by 10 engagement of the bight in the opening 17 and against lateral displacement by embracement of the arm 10 in the opening 18. The ornament may, if desired, be cemented on the bight end of the clasp.

It will be seen that the covered leg 10 extends down through the center of the flower shaped ornament and simulates the stem of the flower. To this end the leg 10 preferably has a green covering which enhances the simulation. It 20 should also be noted that the attachment of the ornament to the clasp is such as not to interfere with the proper functioning of the clasp or with the resiliency of its legs.

To further enhance the ornamental effect, as 25 well as to assist in securing the ornament in place, the member 19, shaped to represent the stamen or pistil of the flower, may be inserted in the cavity 16 of the body 15 and cemented to the leg 10 at the bight end of the clasp. The 30 member 19 also serves to mask the bight of the clasp in the assembled structure.

I claim:

1. A new article of manufacture comprising a spring clasp having two legs and a connecting 35 bight, a hollow ornament mounted on the clasp at its bight end with one leg of the clasp passing through an opening in the ornament and with the bight portion thereof passing through a second opening, whereby to hold the ornament 40 securely in place.

2. A new article of manufacture comprising a spring clasp having two legs and a connecting bight, a hollow ornament mounted on the clasp at its bight end, the two legs of the clasp passing 45 through openings in the ornament at different points, with the bight of said clasp engaged in one of said openings.

3. A new article of manufacture comprising a spring clasp having two legs and a connecting 50 bight, and an ornamental body in the form of an imitation flower mounted on the clasp and supported upon the bight thereof.

4. A new article of manufacture comprising a spring clasp having two legs and a connecting 55

bight, an ornamental body in the form of an imitation flower mounted on the bight end of the clasp with said bight passing through an opening in the body.

5. A new article of manufacture comprising a spring clasp having two legs and a connecting bight, an ornamental body in the form of an imitation flower mounted on the bight end of the clasp, one leg of the clasp extending from the 10 interior through an opening in the body and formed in imitation of the stem of a flower, and the other leg and bight extending through a second opening in said body.

15. A new article of manufacture comprising a spring clasp having two legs and a connecting bight, an ornamental body in the form of an imitation flower mounted on the bight end of the clasp, one leg of the clasp extending from the

interior through an opening in the body and formed in imitation of the stem of a flower, and the other leg and bight extending through a second opening in said body, and a simulated stamen positioned within the ornamental body 5 and secured to the bight end of the clasp.

7. A new article of manufacture comprising a spring clasp having two legs and a connecting bight, and a hollow ornamental body secured to the clasp at its bight end. 10

8. A new article of manufacture comprising a spring clasp having two legs and a connecting bight, and a hollow ornamental body formed in simulation of a flower mounted on the bight end of the clasp, one leg of the clasp protruding 15 through substantially the center of the body in simulation of the stem of the flower.

WILLIAM HUPPERT.
